F. T. WARD

ATTACHMENT FOR BELTS

Filed July 13, 1927

Foster T. Ward INVENTOR

BY Victor J. Evans

ATTORNEY

WITNESS:

R.E. Wiss.

UNITED STATES PATENT OFFICE.

FOSTER T. WARD, OF INEZ, KENTUCKY.

ATTACHMENT FOR BELTS.

Application filed July 13, 1927. Serial No. 205,424.

My present invention has reference to an attachment for belts and is designed to provide a water proof container for articles such for instance as cigarettes and matches.

- 5 The object of the invention is the provision of a belt attachment for this purpose comprising flexibly connected members which will conform to the shape of the belt when the same is arranged around the waist 10 of the user, each of said receptacles having a partly open front, a hinged top, a front plate hingedly secured to the top and having clamping engagement with the bottom of the receptacles for holding the same 15 in closed position and likewise having offset or link connections with slidable members arranged in the receptacle and whereby when the closures are open the said slides will be elevated so that articles may be 20 readily removed therefrom and when the closures are swung to closed position the said slides will be lowered for fully concealing the articles in the receptacle.

To the attainment of the foregoing the 25 improvement resides in the novel construction, combination and operative association of parts, one satisfactory embodiment of which is disclosed by the accompanying drawings.

30 In the drawings:

Figure 1 is a front elevation of my improvement.

Figure 2 is a horizontal sectional view approximately on the line 2—2 of Figure 1.

35 Figure 3 is a sectional view approximately on the line 3—3 of Figure 1.

Figure 4 is a similar sectional view but showing the door or cover in closed position and the receptacle supporting slide in lowered position.

In the preferred embodiment of my improvement I employ two substantially rectangular receptacles, 1 and 2, respectively.

These receptacles are flexibly connected at 45 the back thereof, as indicated by the numeral 3. Each receptacle, on its back, is provided with a looped portion 4 that affords a passage for the belt 5.

As both of the receptacles 1 and 2 are of 50 a similar construction, although of less widths, a detail description of one may be taken as equally applicable in connection with the other although it may be well to state that the wider receptacle 2 is designed 55 primarily for the reception of cigarettes

and the receptacle 1 is designed for the reception of matches. Obviously other articles may be arranged in the receptacles.

Each receptacle upon its outer face is formed with a substantially V-shaped opening 5 that merges into a central restricted opening or passage 6 and the lower wall of this opening 6 is rounded. This arrangement permits of the insertion of the operator's finger in the restricted passage to 60 remove the lowermost article from the receptacle. Preferably the open top of each of the receptacles has its sides arranged at an angle, that is the front is of a less height than the back and this open top is normally 65 closed by a cover plate 7 which is hinged, as at 8, to the back of the receptacle. Hinged, as at 9, to the outer end of the top plate 7 there is a plate 10 that provides the closure for the receptacle. If desired, the 70 closure may be shaped to correspond with the shape of the openings 5 and 6 but is, of course, of a width to fully cover these openings. The cover plate 10 is centrally formed at its outer end with an extension 80 in the nature of a resilient strap 11, and the said strap has an offset hooked end 12 designed to be arranged beneath the open bottom of the receptacle and to frictionally contact with the outer wall provided thereby. The cover or closure plate 10, at its hinge connection 9 with the top 7 has a link 13, and this link is pivotally or hingedly connected to a flange 14 on the upper end of a plate 15. The plate 15 is movable 85 through guides 16 in the back of the receptacle and the lower or inner edge of the plate has an annular portion providing a bottom 17. The bottom has its outer edge in a line with its center notched, as at 18.

95 By an arrangement as above described it will be seen that the opening of the closure plate 9 will elevate the slidable plate 15 so that articles resting upon the bottom of said plate will be raised to permit of the 100 ready withdrawal thereof from the receptacle. By closing the plate the slide is lowered so that the articles are fully concealed in the receptacle. The engaging element 12 between the closure plate and the receptacle 105 affords a water tight joint between these elements so that the articles in these receptacles are fully protected in rainy weather. The improvement may be slid to any desired and convenient position upon 110

the belt 5', and the simplicity of the construction and the advantages thereof will, it is thought, be understood and appreciated by those skilled in the art to which such 5 invention relates, without further detailed description, although it is to be understood that I do not wish to be restricted to the precise details herein set forth and may, therefore, make such changes therefrom as 10 fairly fall within the scope of what I claim.

Having described the invention, I claim:—

In a device for the purpose set forth, a receptacle having loops on the back thereof, an open top and bottom and a partly open 15 front, a top plate hingedly secured to the back of the receptacle, a closure plate

hingedly secured to the outer end of the top plate, said closure plate having a resilient strap extension merging into a hooked end to engage with the outer and lower wall of the receptacle, when the said closure is moved to closed position, a plate guided for 20 slidable movement on the inner wall of the back of the receptacle and having a lower angle end which is centrally notched, said plate having an upper offset portion which is hingedly secured to that of the closure plate, and a link connection between said 25 offset portion and the closure.

In testimony whereof I affix my signature.

FOSTER T. WARD.
